HAIR CUSHION CORD

Wade E. Sackner, Grand Rapids, Mich., assignor
to Grand Rapids Fibre Cord Company, Grand
Rapids, Mich.

Application July 11, 1932. Serial No. 621,771

1 Claim. (Cl. 96—26)

The objects of this invention are:

First, to provide an economical construction of packing or filler cord.

Second, to provide such a cord in which short hair such as is obtained from skins in a tannery may be utilized.

Third, to provide a method for utilizing such hair.

Objects pertaining to details of my invention will appear from the description to follow. A hair cushion cord which is a preferred embodiment of my invention is illustrated in the accompanying drawing, in which:

Fig. 1 is a bat made up of the hair obtained from skins in a tannery.

Fig. 2 is a sectional perspective view of a packing or filler cord showing the use of binding threads opened up at the end to show the construction.

Fig. 3 is an elevation of the finished cord.

Fig. 4 is a section on line 4—4 of Fig. 3 showing the finished cord.

Fig. 5 is an enlarged view of a portion of the bat shown in Fig. 1.

Referring to the drawing, 1 represents a bat of short hair that has been removed from the skins of animals in a tannery. Formerly this hair was used to a great extent in plastering but of late has not been used to such a great extent and it has become desirable to provide a use for such hair. The hair is very short in most instances and a bat of this hair is easily torn apart.

In making use of this hair it is desirable to treat the hair in a garnetting machine to produce a bat such as is shown in Fig. 1. The bat is

then cut into strips, one of which is represented at 2. The edges of the strips are folded over as at 3 and the strips are then run through forming dies of a braiding machine or are compressed in some other way to form a substantially cylindrical cord. The cord thus formed is covered with light threads 4 in the braiding machine.

When the strips are compressed the cord is substantially of the formation shown in Fig. 4.

I am aware that cotton fibres have been wound and incorporated into cords of this kind and in my Patent No. 1,821,582 dated September 1, 1931 for Packing cord, I show a similar treatment of cellulose wadding. The cord which is the subject of this invention is a superior product. It is cheap in construction and is not harmed by water. The use of this method of forming the cord makes it possible to use the short hairs above referred to, and the cord may be made extremely uniform in size.

I desire to claim my invention in the specific form illustrated and also broadly as pointed out in the appended claim.

Having thus described my invention, what I claim as new and desire to secure by Letters Patent, is:

The method of making up a cord comprising garnetting a mass of short hair and forming it into an elongated bat, folding said bat longitudinally on itself, compressing said folded bat into cylindrical form, and braiding wrapping threads therearound while feeding said bat longitudinally of itself.

WADE E. SACKNER.
